UNITED STATES PATENT OFFICE.

FRANCIS H. RICHARDS, OF HARTFORD, CONNECTICUT, ASSIGNOR, BY
MESNE ASSIGNMENTS, OF ONE-HALF TO AMERICAN TYPOGRAPHIC
CORPORATION, A CORPORATION OF NEW JERSEY.

DRIVING MECHANISM.

No. 832,877.

Specification of Letters Patent.

Patented Oct. 9, 1906.

Application filed November 2, 1901. Serial No. 80,868.

To all whom it may concern:

Be it known that I, FRANCIS H. RICHARDS, a citizen of the United States, residing at Hartford, in the county of Hartford and 5 State of Connecticut, have invented certain new and useful Improvements in Driving Mechanism, of which the following is a specification.

This invention relates to the construction 10 and organization, in combination, of various mechanical features and devices for supporting a driving-shaft and effecting its efficient and continued lubrication; and it has for an object to provide a simple compact structure 15 in the nature of a driving-head for supporting and lubricating that end, more especially of a driving-shaft, to which the power for effecting its rotation is applied.

A driving-head constructed in accordance 20 with the present invention possesses means, combined with supports, in which the shaft is mounted for lubricating the various rubbing surfaces by a system of forced lubrication, the circulation of the lubricating material 25 being preferably through a closed circuit. Usually there will be combined in my improved form of driving-head with a sectional shaft a coupling device, whereby the portion or section of the driving-shaft from which 30 power is taken off may be driven from the power-actuated section of the shaft, even though these two sections are not, in alinement or in parallelism one with the other. A driving-head constructed and organized according to the present invention has, moreover, 35 its various mechanical details so combined with and related to each other that the assembling and the taking down of the various parts are facilitated.

40 In the drawings accompanying the present specification a driving mechanism or head embodying the features of my present invention is set forth, Figure 1 therein illustrating, partly in plan view and partly in horizontal section, such a driving-head. Fig. 2 is a longitudinal vertical section taken on the plane of the line 2 2 in Fig. 1, certain of the parts being shown in elevation, however. Fig. 3 is a cross-section on the plane of the 45 line 3 3 in Fig. 2 looking in the direction of the arrow adjacent to that line. Fig. 4 is a cross-section on the plane of the line 4 4 in

Fig. 2 looking in the direction of the arrow adjacent to that line. Fig. 5 is a perspective view of a member detachably connected with 55 the main supporting-frame of the driving-head, in which member there is provided a journal-bearing for that section of the shaft to which the driving-pulley is directly secured. Figs. 6, 7, and 8 are perspective 60 views of various constituent parts of the coupling used in the present illustrated organization for coupling the two sections of the driving-shaft one to the other, a portion of each of these shaft-sections being shown 65 in Figs. 6 and 8. Fig. 9 is an elevational face view of the coupling piece or member proper, showing the head of the screw used for loosely holding the coupling-piece to one of the heads attached to one of the shaft-sections. 70 Fig. 10 is a section on the plane of the line 10 10 in Fig. 9.

Similar characters of reference designate corresponding parts in all figures.

In constructing a driving-head embodying 75 the features of the present invention there will usually be a proper supporting-frame in which the driving-shaft will be mounted. This supporting-frame is herein designated by B and may constitute an integral part of 80 the frame of the mechanism, machine, or apparatus to which the present device is applied, or it may constitute a subframe separate and distinct from such main frame and secured thereto or affixed in place independently thereof. It will usually comprise a 85 base portion, such as 2, upon which there is erected an upright 3, having a journal portion 4, affording a bearing for the driving-shaft.

90 There will preferably be provided in the present driving mechanism or head an organization whereby the main section of the driving-shaft may be driven with a smooth and satisfactory turning movement, even though 95 that portion of the shaft to which the driving power is applied is so disposed in its bearings as to be out of alinement or out of parallelism with that section of the shaft from which power is taken. For this purpose the driving-shaft 100 (designated herein in a general way by S) is sectional, the section s constituting in this case the one from which power is taken, being mounted in the bearing portion 4 of the

upright 3. The other section s' , or that section to which the driving power is applied, is suitably mounted at the other or outer end of the head, the two sections being connected 5 one with the other by a coupling, a suitable form of which will be presently described.

P designates a driving-pulley driven by a belt from a source of power, (not herein shown,) this pulley being secured in this instance to the outer end of the driving-shaft section s' : In order to form a firm support for the section s' , the bearing, therefore, is preferably elongated and advantageously extends some distance into the bore of the 15 pulley P. In fact, the bearing may be so constructed with relation to the latter that it extends beyond the center of the plane of effort of the belt on the pulley. Such is the construction embodied herein, the pulley P 20 having a web p offset to one side of the central transverse plane of the pulley, while the pulley is secured to the shaft-section by any proper means. In this instance the end of the section is reduced in diameter (see 5) 25 and the pulley is attached by a key 6 to such reduced portion, being held in position against the shoulder formed by the reduced portion by the usual nut and washer 7 and 8, respectively. Of course other means may 30 be employed for the attachment of the pulley to its shaft-section.

In order to enable the two sections s and s' of the driving-shaft S to be readily coupled one to another and at the same time permit 35 the section s' to be supported in a proper journal-bearing, which preferably extends substantially throughout its entire length, I prefer to form the bearing for this section in a detachable movable member, which may be 40 removed from the head in order to permit the assembling of the shaft-sections and their connecting-coupling. This removable or detachable member is designated herein by C, and the means for detachably connecting it 45 with the head may be any appropriate for the purpose. As constructed in this instance the attachment of the two is made by means of a so-called "interrupted" or "mutilated" screw, portions of the thread c on the member measured axially thereof and extending peripherally through a considerable distance 50 (see the reduced sections c') being removed, while the bore of the opening in the head 55 with which the member engages is correspondingly formed in the usual and well-known manner. The member C is shown provided with a flange 9, forming a shoulder 9', preferably adapted to make a tight joint with its contacting surface, for a reason that 60 will presently appear. This flange may have openings c'' for engagement with a proper wrench.

Referring now to the coupling device for uniting the two sections of the shaft any 65 construction thereof suitable for the purpose

may be employed. The form herein illustrated is in its general construction familiar to those acquainted with such devices, although embodying certain features of novelty. Referring particularly to Figs. 6 to 10, inclusive, the shaft-sections s and s' are provided with respective heads 10 and 10', which, through an intermediate piece, are capable of transmitting motion from one to the other. As shown in those figures, the head 75 10 is provided with a cross slot or channel 11, while the head 10' is provided with a projecting feather or rib 11'. The coupling-piece, adapted to engage, respectively, with the channel 11 and the feather 11' and serving by reason of such engagement to transmit motion from the shaft-section s' to the shaft-section s , is designated in a general way by C', being formed with a channel 12, adapted to engage with the feather 11' and a feather 12', extending substantially at right angles to the channel 12 and adapted to engage with the channel 11 in the head 10. Evidently when the parts are assembled, with their respective channels and feathers in engagement, the rotation of the shaft-section s' will be transmitted to the shaft-section s , even though the axes of the two sections are not in line and even though such axes are disposed somewhat at an angle to each other, 95 the respective ribs during this rotation sliding to and fro in the channels with which they engage. In order to prevent the accidental displacement of the coupling-piece C' from its proper position with relation to one 100 of the heads with which it engages when the shaft-sections are disassembled, it is here combined with means for securing it to one of said heads, although not in a manner to prevent its proper working. In this case it is 105 adapted to be secured to the head 10' by means of a screw 13, engaging with a tapped opening in such head, and the shaft-section s' to which the head is affixed, the opening in 110 which the shank and head of the screw are located being sufficiently large to permit the free and necessary play of the coupling-piece.

The endwise displacement of the shaft S in its bearings in the member C is prevented by positioning the inner radial face of such 115 member in close relation with the inner face of the head 10' of the coupling when the parts are assembled, while the outer radial face of the elongated bearing in the member C is also in close relation with the radial face of the 120 hub of the pulley P.

The frame B is in the illustrated construction shown provided with an annular extension b, encircling and substantially concentric with the shaft, while in the vertical wall 125 of this extension rearward of the coupling there is a bearing for the sections of the shaft. The end or radial face of the bearing in the wall b' being in close relation to the radial face of the head 10 prevents, therefore, 130

when the coupling is closely assembled, the axial displacement of the main section *s* of the driving-shaft.

There is also shown, combined with the present driving mechanism, means for forcing a lubricating medium to the various journal-bearings supporting the driving-shaft and for circulating such lubricant in a closed circuit in which such bearing portions are included. As a means for circulating the lubricating medium a suitable form of centrifugal or other pump may be used, preferably driven from one or the other of the shaft-sections *s* or *s'*. In the construction and organization herein shown the movable element of this pump, the latter being designated by *D*, is attached to the shaft-section *s*, while the surrounding pump-casing *d* is properly located with reference to said movable element, being prevented from rotation by any suitable means, the form thereof herein shown comprising a lug or finger 14, extending from the casing of the pump and extending when in proper position into a recess between bosses or projections 15 15 on a fixed portion of the frame *B*. The pump illustrated is situated between the shaft-bearings in the rear wall *b'* and the portion 4.

In order to make a convenient reservoir for receiving the drip from the various bearings, the lower or base portion of the frame *B* is shown having a floor with a depression, the sides of the lubricant-receptacle being formed by the casing *E*. The suction-pipe 16 of the pump terminates adjacent to the bottom of such depression, while the discharge-pipe 17 from the pump communicates with a cross-pipe 17', from which leaders or branches extend to proper points for discharging the oil, &c., into openings communicating with the various bearings. In the organization set forth this forced lubrication is directed to a plurality of journal-bearings, that for the shaft-bearing in the portion 4 having an oil-hole 18, immediately above which the discharge-pipe 18' terminates, while the bearing in the end wall *b'* of the frame extension *b* has an oil-opening 19, with respect to which a discharge-pipe 19' is also properly located. The oil-hole 20 for the journal-bearing in the member *C* extends through the extension *b* and through a continuation of such opening in the member *C*, the two passages being in alinement when the member *C* is adjusted to its proper position and the horizontal feeder 17' having a discharge-opening situated above such opening. The oil-groove 20' in the journal-bearing in the member *C*, with which the oil-passage therein communicates, preferably extends to and terminates in that radial face of the member *C* against which the hub of the pulley *P* bears in order to lubricate such surface. The drip from the joint between the face of the hub and the contacting face of the member *C* is received

in a suitable channel *w*, in the present case formed in part by the web of the pulley *P* and in part by a flange 21. The drip in this channel, being naturally thrown outward by centrifugal force toward the bottom of the channel, is returned to the receptacle in the frame *B* by means of a return-pipe 22, secured in a passage-way 21' in the member *C* and communicating therethrough with the space below the coupling-chamber, which has an opening *c'''* in its bottom surface, through which the oil discharges into the receptacle. The outer end of the receiving-pipe 22 is curved around the axis of the driving-shaft concentrically therewith and terminates in close proximity to the bottom of the channel *W* in a position above the driving-shaft to receive the oil in the channel thrown outward against the bottom surface thereof by centrifugal force. The casing *E*, attached to the frame *B*, serves not only to form an oil receptacle or reservoir, but also to inclose the various parts of the head.

Having described my invention, I claim—

1. In a driving-head, the combination with a supporting-frame, of a driving-shaft journaled in bearings in said head, and comprising connected sections; a coupling device for joining the two sections; a bearing member detachably secured to the frame and forming a bearing for one of said sections, and a system for lubricating the different parts through channels formed in said head and bearings.

2. In a driving-head, the combination with a supporting-frame, of a shaft journaled in the head, and comprising connected sections, a detachable member provided with an elongated bearing for one of the shaft-sections, and means actuated from the shaft for forcing a lubricant to the different parts through the head and bearings.

3. In a driving-head, the combination with a supporting-frame, of a shaft journaled in bearings in the head, and comprising connected sections, a detachable member provided with an elongated bearing for one of the shaft-sections, and a lubricating system communicating with lubricating-channels located in said driving-head and bearings.

4. In a driving-head, the combination with a supporting-frame provided with an extension, of a driving-shaft journaled in bearings in the head, and comprising connected shaft-sections; a coupling device for uniting the shaft-sections located in the extension of the supporting-frame; a detachable member in which one of the shaft-sections is journaled and which is detachably secured to the supporting-frame to form one side of said extension and a return system for lubricating the different bearings.

5. In a driving-head, the combination with a supporting-frame provided with an extension, of a driving-shaft journaled in

bearings in the head, and comprising connected shaft-sections; a coupling device for uniting the shaft-sections located in the extension of the supporting-frame; a detachable member in which one of the shaft-sections is journaled and which is detachably secured to the supporting-frame to form one side of said extension, said member having an elongated bearing in which one of the shaft-sections is journaled and a return system for lubricating the different bearings.

6. In a driving-head, the combination with a supporting-frame provided with an extension, of a driving-shaft journaled in bearings

15 in the head, and comprising connected shaft-sections; a coupling device for uniting the shaft-sections located in the extension of the supporting-frame; a detachable member in which one of the shaft-sections is journaled and which is detachably secured to the supporting-frame to form one side of said extension, said member having an elongated bearing in which one of the shaft-sections is journaled; and a driving-pulley secured to this

20 section.

7. In a driving-head, the combination with a frame provided with bearings, of a shaft carried thereby, a member provided with a bearing for the shaft and so carried as to form 30 with an extension, a chamber, and a device for delivering a lubricant to the bearings of the shaft.

8. In a driving-head, the combination with a member, of a shaft journaled therein; a driver secured to the shaft, a drip-channel disposed concentrically with respect to the axis of the shaft, a drip-receiving conduit having its receiving end terminating adjacent to the bottom of said channel, a receptacle for 40 the shaft-lubricant, a device for taking lubricant from the receptacle and delivering it to the bearings of the shaft.

9. In a driving-head, the combination with a frame, a shaft carried thereby, an extension, 45 a member provided with a bearing for the shaft and so carried as to form with said extension a chamber, and a device for delivering the lubricant.

10. In a driving-head, the combination with 50 a supporting-frame, of a lubricating system mounted thereon and connected with the lubricating-supply, a shaft journaled in the bearings in the head, a lubricant-pump mounted on said shaft and connected with 55 said system, the shaft comprising connected sections, a coupling device for uniting the sections, a detachable member provided with an elongated bearing for one of the shaft-sections, a driving-pulley secured to this section, 60 said bearings and head being provided with suitable lubricating-channels communicating with said system.

11. In a driving-head, the combination with a supporting-frame provided with a standard, and an inwardly-extending portion forming 65 a chamber having a lubricating system therein and associated with said frame, a shaft-section journaled in the standard and in said inwardly-extending portion, a lubricant-pump connected with said shaft-section and 70 said system and distributing system leading therefrom, and whose chambers communicate with lubricating-channels in the head and bearings, a detachable member secured to said frame, and a coupling for the shaft securely 75 located in said chamber.

12. In a driving-head, the combination with a frame provided with a bearing and with an extension also formed with a bearing, of a sectional shaft journaled therein; a detachable member provided with a bearing for one of the shaft-sections, and detachably secured to the frame to form, with said extension, a chamber; a device for coupling the shaft-sections together; and a device for delivering 85 a lubricant to the bearings of the shaft.

13. In a driving-head, the combination with a detachable member, of a shaft-section journaled therein; a driving-pulley secured to this section, said pulley being provided with a drip-channel disposed concentrically with respect to the axis of the shaft-section; a drip-receiving conduit having its receiving end terminating adjacent to the bottom of said channel; a receptacle for the shaft-lubricant; a 95 device for taking lubricant from the receptacle and delivering it to the bearings of the shaft-sections; said detachable member having a passage extending from its outer peripheral portion to the bearing-surfaces for the 100 shaft-section journaled therein, and alining, when the member is in its proper position, with the passage into which the lubricant is discharged by said device.

14. In a driving-head, the combination with 105 a supporting-frame provided with a standard and an inwardly-extending portion forming a chamber, of a suction-pump, a shaft-section journaled in said standard and in said inwardly-extending portion; and operating the suction-pump between said standard and said inwardly-extending portion; a suction-inlet for delivering lubricant to the pump; a distributing system leading therefrom, and whose branches terminate above the lubricant 115 openings of the shaft-sections; a detachable member secured to said frame; a coupling for the shaft-sections located in said chamber; and a driving-pulley secured to one of the sections.
